UNITED STATES PATENT OFFICE.

JAY H. KELLER, OF PORTLAND, OREGON.

REGULATING RADIATOR PLUG.

Application filed April 18, 1925. Serial No. 24,056.

To all whom it may concern:

Be it known that I, JAY H. KELLER, a citizen of the United States, residing at Portland, in the county of Multnomah and State 5 of Oregon, have invented a new and useful Regulating Radiator Plug, of which the following is a specification.

My invention relates to regulating radiator plugs in which the longitudinal passage 10 way of a body portion is closed by an obliquely entering regulating screw.

The objects of my invention are to furnish a device which can be manufactured at very little expense; by means of which the 15 regulation of the flow in a radiator can be effected with great nicety and without the necessity of detaching the outlet pipe from the radiator; and which distributes the flow over a large area and thereby minimizes 20 pitting and wire drawing.

Other objects and advantages are to be found in the construction and arrangement of parts as will be described in the specification, and particularly pointed out in the appended claims.

I attain these objects with the mechanism illustrated in the accompanying drawing, in which:

Fig. 1 is a conventional illustration of a 30 radiator with the regulating radiator plug in place.

Fig. 2 is a vertical longitudinal section through the regulating radiator plug.

Fig. 3 is an end view of Fig. 2.

Similar numerals refer to similar parts throughout the several views.

In order to appreciate the import of my invention it may be stated that in hot water heating, especially where forced circulation 40 is employed, the water in the radiators nearest to the boiler will circulate with greater rapidity, and therefore leave to these radiators more than their allotted share of the total heat units, while the radiators located 45 at a farther distance remain comparatively cold.

Hitherto this defect was remedied by unscrewing the outlet pipe of each radiator and then partly closing said outlet with a 50 disk having a small perforation in the center, the size of the perforation however had to be ascertained by trial. In other words, a very small perforation was employed first, and if that proved incorrect, the outlet pipe

had to be unscrewed again and the perforation enlarged, perhaps a number of times, until the water circulated evenly throughout the entire system. Moreover, pitting and wire drawing were apt to enlarge some of the perforations in course of time and the tedious process of equalization had to be repeated anew. In my invention different means and methods are employed, to wit:—

In the radiator 1, having the customary inlet pipe 2, and outlet pipe 3, the regulating radiator plug is inserted between the radiator 1 and the outlet pipe 3. This regulating radiator plug consists of a hollow cylindrical body portion 4 whose one end is provided with the external or male thread 55 65 5 which is to be screwed into the radiator, that same end of the body portion 4 is closed by a vertical wall 6 with a passage way 7 in longitudinal direction near the bottom of the body portion 4. This passage way 75 should be large enough to comply with the maximum requirements of the system. The terminal of the passage way 7 within the chamber 8 is at a portion of the inner side of the wall 6 arranged at an angle to the remaining portion of the wall, and is countersunk at the proper angle to furnish a tight seat for a screw plug 9 which enters the body portion 4 at an angle of approximately forty-five degrees and passes through a 80 85 thickened wall parallel to the valve seat. The outer terminal 10 of the screw plug 9 is square for the use of a wrench or spanner. A counter nut 11 is filled with packing 12 90 insures a steam tight joint. The thread 13 of the screw plug 9 should be of relatively 95 small pitch in order to permit of sufficient refinement in adjustment. That part of the body portion 4 which is entered by the screw plug 9 should be shaped properly to furnish 100 a seat for the counter-nut 11. The end of the body portion opposite the wall 6 is provided with internal thread 14 for the reception of the outlet pipe 3 and preferably given a hexagonal shape to facilitate the application of a wrench or spanner.

Having thus described my invention, it will be seen that my objects have been accomplished and, though I have shown the preferred form of construction, I reserve to myself the right to make minor changes providing I do not violate the spirit and principle of my invention.

I claim:

1. A radiator plug comprising a body adapted to enter a radiator and having an inner vertical wall, a valve seat integral with said wall and at an angle thereto, a second wall parallel to the seat and carrying a valve stem and head cooperating with the seat.
2. A radiator plug comprising a body adapted to enter a radiator and having an inner vertical wall, a valve seat at the bottom end of said wall, said seat being integral with the wall and at an angle thereto, and a second wall parallel to the seat, said sec-

ond wall being thickened and carrying a ¹⁵ valve stem and head cooperating with the seat.

3. A radiator plug comprising an integral body adapted to enter a radiator and having an inner vertical wall, a valve seat integral ²⁰ with said wall and at an angle thereto, a second thickened wall parallel to the seat and carrying a valve stem and head cooperating with the seat.

Signed by me at Portland, Oregon, this ²⁵ 13th day of April, 1925.

JAY H. KELLER.
